WILLIAM A. DOBLE, OF SAN FRANCISCO, CALIFORNIA, ASSIGNOR TO THE PELTON
WATER WHEEL COMPANY, OF SAN FRANCISCO, CALIFORNIA, A CORPORATION OF
CALIFORNIA.

CENTRIFUGAL PUMP.

1,220,403.

Specification of Letters Patent. Patented Mar. 27, 1917.

Application filed June 2, 1913. Serial No. 771,307.

To all whom it may concern:

Be it known that I, WILLIAM A. DOBLE, a citizen of the United States, residing at San Francisco, in the county of San Francisco and State of California, have invented certain new and useful Improvements in Centrifugal Pumps, of which the following is a specification.

This invention relates to pumps and more particularly to pumps of the centrifugal or throwing type. The object of the invention is to provide suitable and efficient means for controlling the capacity and lift of such pumps. In many cases where a pump is used to lift a liquid from a lower level to a higher it is desirable to change the quantity of liquid lifted or the height of the lift. Heretofore this has been done by providing in the discharge conduit leading from the pump, an ordinary valve in which the discharged liquid is throttled by a sudden contraction of the discharge area. The result is an unnecessary loss of energy due to eddy action in the valve and also an early destruction of the valve. To overcome these disadvantages I provide in the discharge conduit a needle-gate valve which is so arranged that the pressure of the liquid is gradually transformed into velocity and after passing the smallest area by which the capacity is controlled the velocity is gradually transformed into pressure again.

The novel features of the invention will be apparent from the following description taken in connection with the accompanying drawings, in which:

Figure 1 shows a centrifugal pump having a needle-gate valve in a casing which is adapted to be bolted or otherwise secured to the discharge outlet of the pump.

Fig. 2 shows a modification in which the discharge conduit of the pump is extended and the valve arranged directly therein.

Referring to the drawings the numeral 10 indicates the pump casing and 11 indicates the rotary member of the pump which is mounted on a shaft 12. The discharge conduit is indicated at 13 and in the embodiment of the invention shown in Fig. 1 the wall of this conduit is provided with an exteriorly arranged flange 14, to which is bolted or otherwise secured the flange 15 of the valve casing 16. Within the valve casing is a needle valve 17 having an enlarged por-

tion 18 which gradually tapers on both sides 55 in the direction of the axis of the valve. The casing 16 is provided with a contracted portion 19 which is of just sufficient size to permit the enlarged portion 18 of the valve to enter therein. The casing is also provided with an enlargement 20 having the conformation of the valve and of such size that when the valve is in the position shown in full in Fig. 1 the annular opening between the valve and the casing will be of approximately the same area as the discharge conduit 13. The valve has a rearwardly projecting stem 21 which passes through a stuffing box 22 in the wall of the casing and is provided with means, such as the hand wheel 23 and screw thread 24, on the exterior of the valve casing for operating the valve.

It will be seen that as the valve is moved from the position shown in Fig. 1 toward the dotted position in the contracted-portion 19 75 of the valve casing the annular area between the casing and the valve will be gradually contracted until the valve enters the portion 19 when the opening will be practically closed. This construction provides for the gradual increase in the velocity of the liquid 80 as it flows past the valve and when the liquid passes beyond the valve into the unrestricted portion of the conduit, the velocity is then converted into pressure. In this way by controlling the opening between the valve and the casing the quantity of discharge and the lift of the pump may be varied at will without the production of eddy currents in the discharge stream and with practically no 90 loss of efficiency. It will also be noticed that the shape of the valve and casing are such that the flow of water will have practically no destructive effect thereon.

In Fig. 2 I have shown a modification of 95 my invention in which the pump casing has been extended to form a discharge conduit, a portion of which forms a valve casing in which I place a valve similar to that shown in Fig. 1 and having similar operating 100 means. This construction is obviously less expensive than that shown in Fig. 1 and eliminates the joint between the valve casing and the discharge conduit. I have shown the valve in Fig. 2 in the closed position, 105 and it will be seen that the valve is opened by a rearward movement thereof to the dotted position.

Having thus described the invention what I claim as new and desire to secure by Letters-Patent is:

In combination, a centrifugal pump including a rotary member and a casing therefor, said casing having a discharge conduit formed integral therewith and having its outlet adapted for connection to a discharge pipe, and a needle valve extending longitudinally of said conduit, said casing having a restricted portion and an enlarged portion through both of which said valve may be moved and which are adapted to coact

with said valve and respectively provide a substantially closed and a full-discharge opening, and said valve being provided with a stem extending rearwardly therefrom and to the exterior of said conduit and provided with means for actuating said valve.

In testimony whereof I affix my signature 20 in presence of two witnesses.

WILLIAM A. DOBLE.
